UNITED STATES PATENT OFFICE.

THOMAS P. BOLGER, OF GLOUCESTER, MASSACHUSETTS, ASSIGNOR TO SUCCESS MANUFACTURING COMPANY, OF GLOUCESTER, MASSACHUSETTS, A CORPORATION OF MASSACHUSETTS.

ASH-SIFTER.

No. 872,640.

Specification of Letters Patent.

Patented Dec. 3, 1907.

Application filed April 8, 1907. Serial No. 367,076.

To all whom it may concern:

Be it known that I, THOMAS P. BOLGER, a citizen of the United States, residing at Gloucester, in the county of Essex and State 5 of Massachusetts, have invented a new and useful Improvement in an Ash-Sifter, of which the following is a specification.

This invention relates to ash sifters and more particularly to means for reciprocating 10 the sieve of the same; the object being to provide the sifter with a shaft provided with a crank carrying a link connected to the sieve, so that the sieve will be reciprocated longitudinally as the shaft is rotated.

15 With this and other objects in view, the invention consists in the novel features of construction, combination and arrangement of parts hereinafter fully described and pointed out in the claims.

20 In the drawings forming a part of this specification:—Figure 1 is a perspective view of my improved sieve showing it arranged on a barrel. Fig. 2 is a longitudinal sectional view of the sifter. Fig. 3 is a vertical sectional view 25 of the same. Fig. 4 is a detail view showing the manner of connecting the sieve to the crank.

Referring to the drawing A indicates a flanged metal cap adapted to fit snugly on 30 an ordinary barrel or ash receptacle having a rectangular shaped opening in the top, on which the rectangular shaped opening of a casing B, is adapted to fit. The side edges A' of the openings of the cap are bent down- 35 wardly into the groove B' formed in the lower ends of the tapering sides B² of the casing. The casing is provided with an inclined end B³ having a hopper C extending upwardly therefrom provided with a hinged top C',

40 the lower end of the end B³ fitting under the flanged edge A³ of the end of the opening of the cap. The upper edges of the sides B² of the casing are provided with outwardly projecting flanges over which the guide edges D' 45 of a top D is adapted to fit, which are provided with a flanged end D² adapted to fit over the flanged edge of the end B⁴ which is secured to the end of the sides and has a reduced lower end forming one side of the

spout E, the other side of which is provided 50 with a flanged upper end fitting under the flanged edge A⁴ of the end of the opening. The side edges of the sides of the spout are flanged to which are secured the depending portion B⁵ of the sides of the casing forming 55 the ends of the spout. A hook F pivotally mounted on the end B⁴ of the casing is provided with an upwardly extending end F' adapted to fit up against the end lid D' when in a vertical position and securely hold the 60 top in place.

Brackets G are secured on the inside of the sides B² of the casing, on which the side bars of the wire sieve H, are mounted. Soldered to the wire netting of the sieve adjacent its 65 upper end, is a bowed bar I over which is looped one end of a link J, the other end of which is looped over the double-crank portion K' of a shaft K, mounted in the side of the casing, under the hopper having a crank handle K² formed on one end by means of which the shaft is rotated, so as to reciprocate the sieve causing the ashes to drop through the 70 sieve into the barrel or receptacle and the coal and cinders to shake down and out the 75 spout into a bucket adapted to be placed on the hook F.

Inclined guide plates L and M are secured to the inside of the front and back of the hopper the plate L guides the ashes on to the 80 sieve, and prevents the ashes from dropping down behind the same when the sieve is forced downwardly.

Having thus fully described my invention, what I claim as new and desire to secure by 85 Letters Patent is:—

A sifter comprising a cap provided with a casing having a hopper at one end, and a spout at the other end, a top slidably mounted on said casing, a hook pivotally mounted 90 on the end of said casing, adapted to engage said top and lock it thereon, a sieve slidably mounted in said casing and means for reciprocating said sieve.

THOMAS P. BOLGER.
